US0D1085049S

(12) **United States Design Patent** (10) **Patent No.:** **US D1,085,049 S**
(45) **Date of Patent:** **** Jul. 22, 2025**

(54) **REMOTE CONTROL WITH KEYBOARD**

(71) Applicant: **Dongguan Yinwei Technology Co., LTD**, Dongguan (CN)

(72) Inventor: **Tangjin Li**, Dongguan (CN)

(**) Term: **15 Years**

(21) Appl. No.: **29/926,555**

(22) Filed: **Jan. 31, 2024**

(51) LOC (15) Cl. **14-03**

(52) U.S. Cl.

USPC **D14/218**

(58) **Field of Classification Search**

USPC ..... D14/218, 388, 456, 496, 400, 401; D13/168, 162–164, 171, 173, 174; D21/333; D11/26, 29, 34, 37, 38 CPC . (57) **CLAIM**

The ornamental design for a remote control with keyboard as shown and described.

DESCRIPTION

FIG. 1 is a perspective view of a remote control with keyboard showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the remote control with keyboard that form no part of the claimed design.

1 Claim, 8 Drawing Sheets
